UNITED STATES PATENT OFFICE.

SETH P. COLGAN, OF ORLEANS, NEBRASKA.

NON-REFILLABLE BOTTLE.

1,183,856.

Specification of Letters Patent. Patented May 23, 1916.

Application filed February 14, 1914. Serial No. 818,708.

To all whom it may concern:

Be it known that I, SETH P. COLGAN, a citizen of the United States of America, residing at Orleans, in the county of Harlan and State of Nebraska, have invented 5 certain new and useful Improvements in Non-Refillable Bottles, of which the following is a specification.

The invention relates to a non-refillable 10 bottle including a gravity seated valve adapted to be held in bottle closing position except in the completely inverted position of the bottle.

The main object of the present invention 15 is the provision of a non-refillable bottle embodying a section adapted to be secured within the bottle neck and formed with a tortuous passage therethrough, the lower end of the passage providing a valve seat, and a 20 gravity operated valve coöperating with said seat and having a pendent portion adapted to coöperate with the section to hold the valve in closed position except on the complete inverting of the bottle.

The invention in its preferred form of 25 details will be described in the following specification, reference being had particularly to the accompanying drawings, in which:—

Figure 1 is a sectional view partly in elevation illustrating the application of the improvement. Fig. 2 is a similar view showing the bottle in a partly inverted position within a tank, illustrating the closed position 35 of the valve and the impossibility of water entering the same in such position. Fig. 3 is a view similar to Fig. 1, showing the bottle inverted. Fig. 4 is a perspective view of the section to be inserted in the bottle neck. Fig. 5 is a section of the valve.

Referring particularly to the accompanying drawings, the improvement comprises a filling section 1 made up of longitudinally divided portions or halves adapted to be 45 snugly inserted within and sealed in the neck 2 of the bottle 3. The section has a lateral annular flange 4 at the upper end adapted to rest upon the upper edge of the neck and forms the pouring rim or lip for emptying 50 the contents of the bottle. Said section is also formed with a longitudinally extending passage 5 of approximately S-shape, which at the upper end is of regular formation to form an opening 6 for the reception of the 55 usual cork 7. The lower end of the passage terminates in a valve seat 8 having an ap-

preciable surface as shown, the bottom surface 9 of the section proper is formed after the shape of a cone.

The valve comprises a stem 10 having 60 spherical terminals 11 and 12, the latter being of greater size than the former. A casting preferably of glass is arranged to inclose the stem and spherical ends, that portion inclosing the end 11 being in the form of a ball 13 of a size to snugly coöperate with the seat 8. That portion of the material inclosing the spherical terminal 12 is in the form of an angular member 14 having a conical lower end 15 and upwardly extending truncated 65 conical upper portion. The relatively upper edge of the portion 16, or that edge next the valve 13, is formed on its outer periphery with a series of closely arranged and upwardly extending slightly flaring fingers 17. 70

In use, the bottle after being initially filled is supplied with a section 1, carrying the valve and the section is sealed in the bottle neck. From Fig. 1 it will be obvious that the valve 13 completely closes the lower 80 end of the tortuous passage 5, the body 14, which is of materially greater weight than that of the valve proper, serving to maintain the valve on its seat. On the partial inversion of the bottle, as illustrated in Fig. 85 2, the upper ends of the fingers 17 will engage the conical surface 9 of the filling section and so maintain the valve on its seat, thus providing a complete closure on a partial inversion of the bottle. On the complete 90 inversion of the bottle, as shown in Fig. 3, the valve will move from its seat until the free ends of the fingers 17 engage the conical portion 9 of the filling section, whereby the fluid may pass freely by the valve into the 95 tortuous passage and so be poured from the bottle. In this position of the valve the fingers 17 act as a strainer for the fluid in the bottle, as will be evident.

The improvement provides a non-refillable 100 attachment which may be readily secured to any bottle, and which when in place will prevent a refilling of the bottle under any conditions, the valve though gravity operated, being prevented from opening except upon 105 complete inversion of the bottle. The parts may be preferably constructed of glass, with the exception of the stem and spherical terminals, and these are preferably completely incased in glass.

What is claimed is:—

A non-refillable bottle having a body and

a neck portion, a filling member located in said neck portion and comprising a pair of longitudinal sections; said filling member having an annular portion overlying the 5 edge of the bottle neck and providing a pouring lip for emptying the bottle's contents, a tortuous passage formed through the filling terminating in a valve seat at one end and a straight portion at the other end 10 adapted to receive the bottle stopper; and a pendent valve having a rigid stem formed on one end with a ball portion adapted to engage with the seat and having a weighted body on the other end adapted to normally

hold said ball portion seated, and a plurality of upwardly projecting fingers formed integrally with said weighted body adapted to keep the valve closed under tilting position of the bottle and providing straining elements when the valve is off of its seat, 15 20 substantially as described.

In testimony whereof I affix my signature in presence of two witnesses.

SETH P. COLGAN.
